SHIP'S PROPELLER WITH BLADES
ADJUSTABLE DURING SERVICE

Fritz Roesch, Lucerne, Switzerland

Application April 25, 1944, Serial No. 532,665

6 Claims. (Cl. 170—160.24)

1

The invention relates to a ship's propeller with blades adjustable during service.

It is known in water turbines to secure the moving blades fitted in the hub by means of collars, these collars having a length in the axial direction of the turbine shaft which is greater than their breadth. The collars of each blade situated inside and outside of the hub, however, are of equal length, which gives rise to the disadvantage that the total angle of adjustment of the blades can only be comparatively small, since otherwise the outer collars which are elongated in an axial direction would require a comparatively large hub diameter in order that the outer edges of the collars should not project beyond the bearing surfaces when the blades are turned.

The limitation to small angles of adjustment for the blades has in the case of ship's propellers the disadvantage that an adjustment of the blades is possible for running ahead but not for running astern. Thus the known design of support for the blades does not fulfill one of the main purposes for the use of variable pitch propellers on ships, namely the simplification and/or improvement of the propelling engine by the elimination of the necessity for reversing the engine.

The invention therefore proposes that the blades should be supported against the hub by means of plate-like bearing surfaces, the outer edges of the inner bearing surface of a blade being further distant from each other in the axial direction than in the direction transverse to this, but that the distance between the outer edges of the outer bearing surface in the axial direction should be smaller than that between the outer edges of the inner bearing surface.

This offers the advantage that the smaller longitudinal extension of the outer bearing surface makes it possible to have a smaller hub diameter in spite of the angle of adjustment being large, a circumstance which is of decisive importance for the efficiency of marine propellers.

Above all it will be advantageous if the outer bearing surface of a blade is designed with a circular outer shape, for in this way not only can the sealing of a blade be simplified but the outer bearing surface can also be arranged completely within the packing, which is of essential importance for faultless service. Only in this way can the fouling and damaging of the bearing surfaces be precluded and faultless lubrication ensured.

2

In the drawings several embodiments of the invention are shown diagrammatically.

Figs. 1 and 2 show a longitudinal section and a composite view respectively of a propeller hub with supporting plates designed in one piece. The right half of Fig. 2 is a top view of the device shown in Fig. 1 with the propeller blade and its retainer member removed. The lower left portion of Fig. 2 is a top view of the device shown in Fig. 1. The upper left portion of Fig. 2 is a top view of the device shown in Fig. 1 with the propeller blade and intermediary member removed from its inner bearing member.

Fig. 3 is a longitudinal sectional view of a modified propeller blade pitch changing mechanism according to the invention.

Fig. 4 shows a portion of a section of the mechanism shown in Fig. 3, taken along line IV of said figure.

Fig. 5 is a top view of the mechanism shown in Figs. 3 and 4 with the propeller blade and intermediary member removed and part of the hub cut away.

Fig. 6 is a rear view of the mechanism illustrated in Figs. 3 to 5.

Fig. 7 shows the part of the hub carrying the blades designed in one piece, with the blades provided with supporting plates and the hub attached to the shaft by means of a nut situated in front of the hub.

Figs. 8 and 9 show a blade-carrying part in one piece with linkage members serving for the adjustment of the blades arranged in the hub in front of this blade-carrying part.

The propeller with its hub 2 and its blades 3, the number of which is ordinarily from two to four, is attached to the propeller shaft 1 by means of the tapered shaft end 4 and the nut 5. The blades 3 can be adjusted during service. In

40 the hollow shaft 1 is provided the push rod 6 with the cross-piece 7 attached to it. The push rod is moved backwards and forwards in the axial direction by means of a device, operated by hand or by a servomotor and not shown in the drawing.

45 The bearings 8 and 9 provide parallel guiding for one connecting rod 10 for each blade 3, and this rod has a pin 11 which is surrounded by the slide block 12. The slide block 12 slides in the groove 13 provided in the inner bearing member 26, and when the rod 6 or the connecting rod 10 is axially displaced, brings about a turning of the member 26 and thereby of blade 3 about the center pin 14.

50 55 The root portion of blade 3 is rotatably sup-

ported in the hub 2 by means of the inner and outer thrust bearing surfaces 15 and 16, which take the form of plates. The outer edges 17 and 18, that is the outer limits of the inner bearing surface 15 of a blade 3, are further distant from each other in the direction of the axis 19 than the edges, that is the corners 20 and 21, in a direction transverse to this axis. The whole inner bearing surface 15 thus has a form which is elongated in the axial direction 19, while the breadth of it is shortened transverse to the axial direction 19, a circumstance which allows a smaller diameter of the hub 2 to be obtained than would be the case with a circular inner bearing surface having a diameter equal to the outer distance 17, 18. Further, the distance in the axial direction 19 between the outer edges 22 of the outer bearing surface 16 is considerably, for instance 20%, smaller than the distance between the edges 17 and 18 of the inner bearing surface 15.

This elongated inner support 15 is entirely adapted to the forces presenting themselves in the blade, since the bearing surface is greater in the direction at right angles to the plane of the blade than in the direction transverse to this. The thrust resulting from the flow along the blade is in fact almost at right angles to the surface plane of the blade. The elongated form of the inner bearing surface also provides a wide base for the supporting surface, and the centres of gravity of the forward and aft segmental parts of the bearing surface 15 can be at almost any distance from each other, as this distance can be great even when the width of the surface 15 is small and thus the diameter of the hub 2 is small, a situation which contrasts with that presenting itself in the case of a circular inner bearing surface.

As with plate bearings the inner bearing surface also has to take the considerable centrifugal forces, the elongated form of the inner bearing surface enables the area of the surface in cm.² to be chosen as great as desired even when the diameter of the hub is small, and thus enables the specific loading to be kept small, above all because the area of the outer bearing surface can be kept small in spite of having a small specific loading.

It would also be possible for the outer bearing surface 16 to be, like the inner bearing surface 15, longer in the axial direction 19 than in the direction transverse to this. In Figs. 1 and 2 the outer bearing surface 16, however, has a circular outer form. This has the advantage that the packing can be arranged in a groove 23 around the outside of the outer bearing surface 16, and the sealing towards the outside can thus be effected in a simple and adequate manner. If the outer bearing surface 16 were also elongated, at least the outer sealing surface could be circular.

The blade 3 has a circular root flange 24, which is connected by the bolts 27 with the outer supporting plate 25 and the inner supporting plate 26. While the outer plate 25 is of circular design, the inner plate 26 has an elongated form to correspond to the design of the bearing surface 15 and is centred on the outer plate 25 by means of the projection 28.

The two plates 25 and 26 are supported against the elongated piece 29. The form of this can be seen from Fig. 2. The lower left-hand quarter of the drawing shows the hub 2 from the outside with the blade 3 in place, the upper left-hand quarter shows the hub without the blade 3 and

without the upper supporting plate 25, so that the piece 29 is visible with the groove 23. The right-hand half of Fig. 2 shows the hub 2 without the piece 29 and in particular the forward end of the inner bearing plate 26, the aft end of which has the same design.

The piece 29 is attached by means of the bolts 30 to the hub 2 and is sealed by means of the packing 31 (Fig. 1). Thus the blades 3, with their hub portions composed of pieces 25, 26, and supporting shell plate 29, can be introduced into the shell of hub 2 as one unit and bolted to it. This offers the advantage that the bearing surfaces 15 and 16 on the piece 29 can be machined in a simple manner and easily fitted to the bearing surfaces 15 and 16 of the plates 26 and 25. Towards the rear the hub 2 is closed in the usual manner by means of a hood 32 consisting of two parts.

While in Figs. 1 and 2 the hub 2 is attached to the shaft 1 by means of the tapered end 4, in Fig. 3 the shaft 1 is provided with a flange 33 and attached to the end wall 35 of the hub 36 by bolts 34 distributed around the circumference of the flange 33, while it is centred by means of a projecting piece. The blades 3 are provided with a circular root 37 which is centred on the outer supporting plate 38 and attached to it by means of the stud bolts 39 and the nuts 40.

The inner supporting plate is designed in several parts. While the parts 43 and 44 are provided with the bearing surfaces 41 and 42, the middle part 45 of the inner supporting plate has a pin 46 which is fitted in the bearing 47. For each blade 3 a similar bearing 47 is present, and these are all connected to the end wall 35 of the hub 36 by means of the sleeve 48. Both the bearing surfaces 41 and 42 of the inner plate 43 to 45 and also the bearing surfaces 49 of the outer plate 38 are of tapered design, and the outer plate 38 is sealed by means of the packing 50.

The tapered design of the bearing surfaces 41, 42, 49 makes it possible for the layer of metal of the hub between the blades 3 to be sufficient even when a large number of blades is employed and above all for the diameter of the hub to be reduced in that both the plates 38, 43, 44 and also the hub piece 36 are sufficiently thick at the place where the bearing surfaces 41, 42, 49 begin, while the thickness of these pieces at their ends can be small.

The design of the supporting plate 43—45 in several parts enables it to be erected without a specially inserted supporting piece, such as the piece 29 in Figs. 1 and 2, as the parts 43 and 44 are passed through the circular opening 51 individually and the part 45 is afterwards placed between them, whereupon all three are connected to the outer plate 38 by means of the stud bolts 39.

An adjusting shaft 52 is provided for adjusting the blades 3 and upon it is fixed, by means of a tapered end and a nut, the spider 53. This spider has for each blade a slide block 54, this being designed in two parts and enclosing the ball 55, which is attached to the aft part 43 of the inner supporting plate 43—45.

By operating the blades 3 by means of an adjusting shaft and a spider, it is possible to connect the sleeve 48 and the bearing 47 rigidly to the outer jacket of the hub 36 by means of the stays 56 (Fig. 4) which form continuous longitudinal walls through the hub. If a connecting rod with parallel guiding, such as the rod 10 in

Figs. 1 and 2, or a known form of link were used for adjusting the blades 3, the stays 56 would have to be omitted. If a link were employed, the inner plate 43 to 45 would have to be provided with a pin in place of the slide block 12 in Fig. 2, while the cross-piece 7 in Fig. 1 would have to have a pin or bolt for each blade 3.

A further reduction on the maximum diameter of the hub 2 or 36 can be obtained by letting the lateral edges 57 and 58 of an inner plate, such as the plate 26 in Figs. 1 and 2 or the parts 43 and 44 in Figs. 3 and 5, run parallel not to each other but to the axis 19 of the hub, when the blades 3 are in one or other of the end positions. The spider is protected by the hood 59.

This special design of the lateral edges 57, 58 of the bearing surfaces 15 or 41 and 42, a design similar to the form of a bricklayer's trowel, offers the advantage that with a small hub diameter a large angle of adjustment for the blades 3 is possible. Thus, for instance the angle of adjustment in known rotors of water turbines is only 15° at a hub diameter of 3.5 times the shaft diameter or at a ratio of the hub diameter to the rotor diameter of 0.35, while in Figs. 1 and 2 the total angle 2α amounts to 60° at a diameter of the hub 2 equal to 2.54 times the diameter of the shaft 1, and the angle of adjustment is thus considerably larger in spite of the smaller hub. By this means it is possible for the blades 3 to be adjusted both for running ahead and running astern.

The tapered design of the bearing surface leads to a still smaller hub diameter of 2.30 times the diameter of the shaft 1 in Figs. 3 to 6. The angle β is 50°, but if the blades 3 are adjusted by means of the push rod 6, as in Fig. 1, instead of by an adjusting shaft 52, it might be just as large as the angle 2α in Fig. 2. The ratio of the diameter of the propeller to the diameter of the hub 2 or 36 in the plane of the blades 3 amounts to 0.25 at the most with a propeller as in Figs. 1 and 2, and with a propeller as in Figs. 3 to 6 to 0.23 or less.

The angle γ in Fig. 6 shows the turning of the adjusting shaft 52 when the blades 3 are adjusted through the angle β .

The cross-section VI—VI in Fig. 3 and all other cross-sections parallel to it through the hub 36 are circular in shape, while the longitudinal section of the hub 36 passing through the axis 19 has an elliptical form, so that the hub 36 is designed as an ellipsoid and has the advantage of being adapted to the elongated form of the inner supporting plate while it is also favourable for the flow of water over the hub.

The propeller 101 in Fig. 7, with two or more blades 102 which are adjustable during service, has part 103 which carries the blades 102 and which is closed towards the rear by a protective hood 104. The blade-carrying part 103 has on each side of the blades 102 an end wall 105 and 106 connected to the parts supporting the blades. These two end walls are both attached to the propeller shaft 107 and are connected by the sleeve 108 which surrounds the shaft 107 and which has a tapered bore. The adjustment of the blades 102 is done by means of the linkage parts arranged inside the hub, i. e. by the links 14, which are attached at their aft end to the cross-piece 15 which is in its turn attached to the push rod 16. The push rod 16 leads to an auxiliary device for adjusting the blades 102 situated in the body of the ship and not shown in the drawing. The end wall 106 can be attached to the sleeve

108 and detachably bolted to the outer wall 111.

The blades 102 are provided with an inner supporting plate 122 and an outer supporting plate 123, both of which rest on the bearing ring 124. 5 The ring 124 is rigidly attached around its circumference to the blade carrying part 103 of the hub by means of bolts 125. The inner supporting plate 122 is attached to and centred on the neck 121 of the blade 102 by means of the bolt 126. 10 The plate 122 is provided on its internal face with a pin for the link 114. The root of the blade 102 is sealed against the entry of water or the escape of oil by means of the packing 128.

For the purpose of attaching the propeller 101 15 to the tapered end 117 of the propeller shaft 107, the part 103 is provided at its forward end with a thread 129. The propeller shaft 107 has a thread 130, which either has a different pitch from the thread 129 or differs from it in that, for instance, 20 one of the threads is left-handed while the other is right-handed. The hub is attached by means of the nut 131. The key 120 is provided to secure the parts against relative turning.

The propeller shaft 107 may also, in accordance with a known arrangement, have a thread 25 on which a nut is screwed which presses the sleeve 108 firmly upon the tapered shaft end 117.

The flux of force between the propeller shaft 101 and each blade is at no point strongly concentrated, but passes directly from the propeller shaft 107 to the end walls 105 and 106 and through the ring 124 and the plates 122 and 123 to the blades 102, so that there is a broad and well distributed flux of force between the propeller shaft 107 and the blades 102.

In the case of shocks to the propeller 101, the blade supports 122, 123 are held firm on both sides by the end walls 105 and 106. The fact that the part 103 is fitted along the whole length of 30 the tapered shaft end 117 by means of the sleeve 108 guarantees the rigid attachment of the propeller 101.

The support arrangement of the blades in Fig. 8 is the same as in Figs. 1 and 2, the blade carrying part 103 of the hub is, as in Fig. 7, designed in one piece. The part 134 of the lower supporting plate is provided with a lever arm 158, which is designed at its forward end 159 as a ball and is surrounded by a slide block 160 which is situated in the spider 161 (Fig. 9). The spider 161 is rigidly fixed on the tapered end of the sleeve 162, surrounding the propeller shaft 107, by means of a key and the nut 163, and the hub 101 is sealed at its forward end by means of the cap 164 with 55 the stuffing-box 165, so that the linkage parts 158, 160 and 161 serving for the adjustment of the blades 102 are arranged so as to be watertight inside the hub 101.

The adjustment of the blades 102 is effected 60 by turning the sleeve 162, which is provided at its forward end with a steep-pitch thread 166. The sleeve 167 has at its left-hand end an internal thread corresponding to the thread 166 and is secured against turning and guided in the axial 65 direction of the propeller shaft 107 by means of the key 168 at its right-hand end. The lever 169 turns about the pin 170 and encircles the sleeve 167. It is provided with two pins 171 which project into the groove 172 of the sleeve 167. The toothed quadrant 173 holds the lever 169 firmly 70 in position.

When the lever 169 is adjusted, the sleeve 167 is pushed backwards in an axial direction and, on account of the steep-pitch thread 166 the sleeve 162 and with it the spider 161 are turned 75

relative to the propeller shaft 107. The slide blocks 160 turn about the propeller shaft 107 and carry the ball joint 159 with them, so that the blades 102 are turned about their axis.

The thread 166 can have a pitch of such a type that it is self-locking and any turning of the sleeve 162 under the influence of a torque at the blades 102 is obviated. The advantage of this design consists in that the diameter of the hub is small since the shaft does not need to have a bore and the same comparatively small dimensions can be kept as are employed with fixed blades. This advantage makes itself very noticeably felt in particular with propeller diameters below 1.5 or even 2 metres. The sleeve 162 serves at the same time as a protection and a support for the shaft 107. It is sufficient for the sleeve 162 to lie close against the propeller shaft 107 in the neighbourhood of the stern tube bearing 174 and at its ends, while it may have a somewhat wider bore between these points.

I claim:

1. In a variable pitch propeller, a hub member, a propeller blade having a blade root portion rotatably mounted in said hub member, said blade root portion comprising two thrust bearings axially spaced on the blade axis, the thrust bearing closer to the propeller axis being adapted to receive the thrust acting in the direction away from the propeller axis and having a thrust bearing portion extending radially of the blade axis and projecting beyond the other thrust bearing and being tapered as it extends radially out.
2. In a variable pitch propeller, a hub member, a propeller blade having a blade root portion rotatably mounted in said hub member, said blade root portion comprising two thrust bearings axially spaced on the blade axis, the thrust bearing closer to the propeller axis being adapted to receive the thrust acting in the direction away from the propeller and being composed of a plurality of individual thrust bearing members, at least one of said members extending radially of the blade axis beyond the other thrust bearing.
3. In a variable pitch propeller, a hub member, a propeller blade having a blade root portion rotatably mounted in said hub member, said blade root portion comprising two thrust bearings axially spaced on the blade axis, the thrust bearing closer to the propeller axis being adapted to receive the thrust acting in the direction away from the propeller axis and having two diametrically opposed portions extending radially of the blade axis and beyond the other thrust bearing and being tapered in a direction parallel to the rotation axis of the propeller as they extend out.
4. In a variable pitch propeller, a hub member, a propeller blade having a blade root portion rotatably mounted in said hub member, said blade root portion comprising two thrust bearings axially spaced on the blade axis, the thrust bearing closer to the propeller axis being adapted to re-

ceive the thrust acting in the direction away from the propeller axis and comprising an annular portion and a portion extending from said annular portion and radially of the blade axis and beyond the other thrust bearing, and a pitch varying mechanism radially slidably connected with said annular portion.

5. In a variable pitch propeller, a hub member, a propeller blade having a blade root portion rotatably mounted in said hub member, said blade root portion comprising two thrust bearings axially spaced on the blade axis, the thrust bearing closer to the propeller axis having a projecting portion extending radially of the blade axis and beyond the other thrust bearing, and pin means disposed coaxially with said root portion and rotatably interconnecting said hub member and the thrust bearing which is closer to the propeller axis than the other bearing.
6. In a variable pitch propeller, the combination of a hub member, a supporting shell plate having a marginal portion removably secured to said hub member, and a propeller blade having a thrust bearing outside of and adjacent to said shell plate, a blade root portion rotatably mounted in said shell plate, and a bearing means connected to said blade root portion and extending substantially radially of the blade axis at the inside of said shell plate and having portions extending radially of the blade axis farther than said thrust bearing but not as far as the marginal portion of said shell plate.
